CLAIM

The ornamental design for a face shield, as shown and described.

DESCRIPTION

FIG. 1 is a top plan view of a face shield showing my new design, with the face shield in a down position;

FIG. 2 is a right side elevational view thereof;

FIG. 3 is a front elevational view thereof;

FIG. 4 is a bottom plan view thereof;

FIG. 5 is a left side elevational view thereof;

FIG. 6 is a rear elevational view thereof;

FIG. 7 is a left side elevational view thereof, the face shield shown in an up position; and,

FIG. 8 is a top frontal perspective view thereof. The man shown in broken lines in FIGS. 2, 5 and 7, is shown for illustrative purposes only and forms no part of the claimed design.

FIG. 1

FIG. 2

FIG. 3

FIG. 4

FIG. 5

FIG. 6

FIG. 8

FIG. 7
